UNITED STATES PATENT OFFICE.

PAUL F. W. C. KRIPPENDORF, OF LYNN, MASSACHUSETTS, ASSIGNEE TO KRIPPENDORF KALCULATOR COMPANY, OF PORTLAND, MAINE, A CORPORATION OF MAINE.

COMPUTING DEVICE.

1,142,182.

Specification of Letters Patent.

Patented June 8, 1915.

Application filed April 1, 1908. Serial No. 424,557.

To all whom it may concern:

Be it known that I, PAUL F. W. C. KRIPPENDORF, a citizen of the United States, and a resident of Lynn, in the county of Essex and State of Massachusetts, have invented an Improvement in Computing Devices, of which the following description, in connection with the accompanying drawing, is a specification, like letters on the drawing representing like parts.

This invention relates to a device for automatically computing or calculating the superficial area required in different materials to provide for the cutting of a plurality of irregular shaped parts therefrom.

It is particularly designed for use in the manufacture of shoes where it is desired to ascertain the superficial area of any kind or quality of leather which will be required to

20 cut therefrom the whole or any part of a shoe.

The device is designed when applied to any particular part or parts of a shoe of any style or shape to calculate and indicate 25 automatically the superficial area of leather required to cut out the part or parts in question, including the allowance for wastage due to the particular kind of leather, size of skins, etc., as well as, if desired, a fixed 30 allowance determined by the manufacturer.

The device of this invention is particularly designed for use in connection with the calculating device shown and described in application No. 419,650, filed March 7th, 35 and its object when so used with such device is to furnish accurately directly and without the necessity for supplementary calculations, the data required for the table, such as set forth in said application. A

40 table such as that referred to shows the amount of leather which it is desired to allow, or in other words, the total superficial area required for the cutting of the whole or any part or group of parts of any

45 style of shoe of the standard size $4\frac{1}{2}$ C. It is obvious that since this table forms the basis of the subsequent calculations of the amount of leather required to cut large quantities of shoes in the factory, that to

50 secure the best results it must be as accurate as possible. One of the factors upon which the table is based is the actual size of the parts of the particular style of shoe.

55 This invention renders it possible to secure accurate results by the employment of the

device herein disclosed which measures the actual area of the parts of the shoe, and automatically makes and indicates the required allowances.

The invention will appear more fully 60 from the accompanying description and drawings and will be more particularly pointed out in the claims.

The drawings represent the preferred 65 form of the invention.

Figure 1 is a top plan view of the device shown in operative position. Fig. 2 is a cross-section taken through the line x—x. Fig. 3 is a top plan view of the circular 70 scale of the device.

The device is based on the principle of the polar planimeter and should be of a size suitable for easily passing around the periphery of any size of shoe part.

The device comprises a radius arm A, the 75 precise length of which is immaterial, and which is arranged to move about a fixed pivot B. For that purpose the pivot B may be mounted on a weight C, which can be set at any point on the table on which the 80 device is used.

The device further comprises the tracing arm D, provided at one end with a tracing point D², and pivoted at its opposite end at D³ to the radius arm A. This pivot D³ is 85 mounted in a slide D⁴ which may be set at any position along the tracing arm D and clamped by means of the set-screw D⁵ so that the effective length of the tracing arm, that is, the length from the tracing point 90 D² to the pivot D³, may be varied.

The device further comprises the wheel E, mounted on the transverse shaft E². The shaft E² is sustained in position by having its conical or rounded ends seated in 95 depressions in the adjustable journal screws E³, mounted in an annular bearing block E⁴.

The bearing block E⁴ is sustained in a circular enlargement F of the tracing arm D, and in the construction shown the bearing block E⁴ and enlargement F have corresponding conical walls so as to secure a close fit without lost motion. A cap-plate G is screwed on to the upper surface of the bearing-block E⁴ and extends over and slides 100 upon the enlargement F, and is provided with oppositely arranged spring fingers G², pointed at their ends to take into the holes of the scale S shown in Fig. 3.

110 It will thus be seen that by raising the

spring fingers G^2 and turning the plate G the bearing block E^4 may be set at any position angularly with respect to the enlargement F of the tracing arm, and that thereupon the axis of rotation of the wheel E will take any desired angle with respect to the vertical plane of the axis of the tracing arm. The parts are so constructed that the vertical axis of the wheel E is on the center of rotation of the bearing block E^4 , and in the vertical plane of the axis of the tracing arm or the vertical plane passing through the tracing point D^2 and the pivot D^3 it being understood that the device is operating on a horizontal plane.

An indicator H of any suitable type, such for example as the ordinary cyclometer type, is carried by the bearing block E^4 and operated by the rotation of the wheel E , so as to indicate in figures the result of the rotation of the wheel E .

Near the end of the tracing arm D a pin D^6 is mounted, and is of such a length as to rest upon the article being measured and prevent the tracing point from scratching the same.

When the wheel E of the device is set at an angle of 90° , or at right angles to the axis of the tracing arm, and the tracing point D^2 is moved entirely around the periphery of an irregular shaped figure, such as a shoe part illustrated in Fig. 1, the exact area of the figure or shoe part will, under the well known principle of the polar planimeter, be equal to the length of the tracing arm multiplied by the distance rolled over by the periphery of the wheel. Hence, the indicator H for a given diameter of wheel, may readily be arranged to indicate in figures the exact area. In the manufacture of shoes, however, it is desired to ascertain the superficial area which would be required to cut therefrom the part or parts of a shoe which obviously will be greater than the exact area of the part or parts to be cut, and will vary according to the particular kind of leather, the size of the skins, etc., to be used. The relations between these latter factors is, however, well known as the result of wide experience, and can be expressed in figures. For example, if it requires a certain amount of leather to cut certain parts of a shoe from calf it is known what percentage of that amount will be required to cut the same parts from patent leather. Again, if a certain amount of leather is required to cut the parts of a shoe from an eight foot skin, it is known what percentage of that amount will be required to cut the same parts from a six foot skin. This ratio, as a result of many experiments, and a wide experience, may be indicated as follows for the factors here set forth, but it is obvious that other factors may enter into the matter and may be given a number

to correspond to their effect. The table is illustrative merely.

2.00	3.00	
2.10	3.10	
2.20	3.20	Kid 8 ft. skin 70
2.30	3.30	
2.40	3.40	
2.50	3.50	
2.60	Patent colt	3.60
2.70		3.70 75
2.80	Russia calf	3.80
2.90		3.90
		4.00

As already explained the area indicated on the indicator H will be equal to the length of the tracing arm multiplied by the distance rolled over by the periphery of the wheel. Hence it follows that if the angular position of the wheel with respect to the axis of the tracing arm be changed the indicator will show a fraction, proper or improper, of the actual area of the part being measured. The distance rolled over by the wheel, being one of the factors which goes to make up the area, will vary with a change of the angular position of the wheel directly as the cosine of the angle which the wheel makes with the axis of the tracing arm. It follows, therefore, that if the scale S be graduated by angles whose natural cosines are the ratios existing between the different kinds of leather, different sizes of skins, etc., or the ratios existing between the numbers such as set forth in the foregoing table, that the wheel E when positioned according to the said graduations will multiply or divide the actual area of the part being measured accordingly. For convenience these graduations are arranged as shown in Fig. 3, the odd numbers appearing on one quadrant, and the even numbers on the diagonally opposite quadrant, and the indicator H is arranged to show the actual area of the part being measured when the wheel E is set to the graduation 2.00. It is also apparent that by varying the effective length of the tracing arm D the result shown by the indicator will be varied in proportion to the effective length of the tracing arm. It is desirable to have such a variation of the total result show that any manufacturer may increase or diminish the allowance which he desires to make by a fixed percentage. For example, if it is desired to improve the quality of the shoes being manufactured the amount of leather allowed to the cutters may be increased, and correspondingly when it is desired to diminish the cost of production the amount of leather may be decreased. Any such increases or decreases will, it will be observed, be independent of the kind, quality of leather, or size of skins, etc., being used. The tracing arm, accordingly, is marked off as shown

at T in percentages. The construction is such that when the slide D⁴ is at 1.00 the scale H will show the area as modified by the allowances of the scale S. This area will 5 increase or decrease accordingly as the slide D⁴ is shifted to one of the other graduations on the scale T.

The operation of the device will now be apparent, and may best be illustrated by a 10 concrete example. Let us assume that the manufacturer desires to take up the manufacture of a particular style of shoe. He determines first the kind of leather, the size of skin, etc., which he is to use, and after 15 consulting the table hereinbefore set forth sets the pointer G² of the device at the corresponding graduation on the scale S. If he desires to make no change in the allowance, which is just sufficient for cutting the 20 parts, he sets the slide D⁴ at 1.00 on the scale T. If, however, he desires to increase the allowance slightly, say five per cent., to allow of the production of a high grade 25 shoe, he sets the slide at 1.05 on the scale T. He then takes the patterns of the standard size 4½ C of the different parts which are to be cut, places them upon the table singly or in groups, as desired, and runs the tracer D² around the periphery thereof. When 30 this is completed the indicator H shows in figures the total superficial area required with all allowances for cutting the part or parts in question. By repeating this operation the figures are obtained for making a 35 table such as that shown in the aforesaid application Serial No. 419,650.

Having described my invention, what I claim as new and desire to secure by Letters Patent, is:

40 1. A measuring and calculating device of the character described, comprising a tracing arm provided with a tracing point, a radius arm pivoted to the tracing arm, a wheel mounted on the tracing arm to rotate about an axis in the vertical plane of the axis of said arm, and means to allow of the adjustment of said wheel to vary the angular position of its axis of rotation with respect to said plane.

50 2. A measuring and calculating device of the character described, comprising a tracing arm provided with a tracing point, a radius arm pivoted to the tracing arm, a wheel mounted on the tracing arm to rotate about an axis in the vertical plane of the axis of said arm, and means to allow of the adjustment of said wheel to vary the angular position of its axis of rotation with respect to said plane, and an indicator oper- 55 atively connected with said wheel and operated thereby to indicate the desired area.

60 3. A measuring and calculating device of the character described, comprising a tracing arm provided with a tracing point, a radius arm pivoted to the tracing arm, a

wheel mounted on the tracing arm to rotate about an axis in the vertical plane of the axis of said arm, means to allow of the adjustment of said wheel to vary the angular position of its axis of rotation with respect 70 to said plane, and graduations on the tracing arm to indicate the angular position of the wheel.

4. A measuring and calculating device of the character described, comprising a tracing arm provided with a tracing point, a radius arm pivoted to the tracing arm, a wheel mounted on the tracing arm to rotate about an axis in the vertical plane of the axis of said arm, means to allow of the adjustment of said wheel to vary the angular position of its axis of rotation with respect 75 to said plane, and graduations on the tracing arm to indicate the angular position of the wheel, and an indicator operatively connected with said wheel and operated thereby to indicate the desired area.

5. A measuring instrument of the character described, comprising a tracing arm provided with a tracing point, a radius arm pivoted to the tracing arm, connecting means permitting the pivotal point of said arms to be adjusted to or from the tracing point to vary the effective length of the tracing arm, and indicating means adjustable to 90 determine a predetermined fraction of the area bounded in the movement of the tracing arm.

6. A measuring and calculating device of the character described, comprising a tracing arm provided with a tracing point, a radius arm pivoted to the tracing arm, means whereby the pivotal point of the said arms may be adjusted to or from the tracing point to vary the effective length of the tracing arm, a wheel mounted on the tracing arm to rotate about an axis in the vertical plane of the axis of said arm, and means to allow of the adjustment of said wheel to vary the angular position of its axis of rotation with respect to said plane.

7. A measuring and calculating device of the character described, comprising a tracing arm provided with a tracing point, a radius arm pivoted to the tracing arm, means 115 whereby the pivotal point of the said arms may be adjusted to or from the tracing point to vary the effective length of the tracing arm, a wheel mounted on the tracing arm to rotate about an axis in the vertical plane 120 of the axis of said arm, and means to allow of the adjustment of said wheel to vary the angular position of its axis of rotation with respect to said plane, and an indicator operatively connected with said wheel and operated to indicate the desired area.

8. A device for measuring the area of shoe parts and calculating the amount of leather required for cutting the same, comprising a tracing arm provided with a trac- 125

ing point, a radius arm pivoted to the tracing arm, graduations on the tracing arm to indicate the manufacturer's allowance, means whereby the pivotal point of said arms may be adjusted to either of said graduations, a wheel mounted on the tracing arm to rotate about an axis in the vertical plane of the axis of said arm, and having its axis of rotation adjustable angularly with respect to said plane, graduations on the tracing arm to indicate the angular position of the wheel and thus the kind of leather to be used, and an indicator operatively connected with said wheel and operated thereby to indicate the desired area.

9. A device for measuring the area of shoe parts and calculating the amount of material required for cutting, a tracing arm provided with a tracing point, a radius arm pivoted to the tracing arm, a wheel mounted on the tracing arm to rotate about an axis in the vertical plane of the axis of said arm and having its axis of rotation adjustable angularly with respect to said plane, angular graduations on the tracing arm, the natural cosines of which correspond to the ratios existing between the superficial area of different kinds of leather required to cut the same given shoe parts, and an indicator operatively connected with said wheel and operated thereby to indicate the desired area.

10. A device for measuring the area of shoe parts and calculating the amount of leather required for cutting the same, comprising a tracing arm provided with a tracing point, a radius arm pivoted to the tracing arm, graduations on the tracing arm to indicate the manufacturer's allowance, means whereby the pivotal point of said arms may be adjusted to either of said grad-

uations, a wheel mounted on the tracing arm to rotate about an axis in the vertical plane of the axis of said arm, and having its axis of rotation adjustable angularly with respect to said plane, graduations on the tracing arm to indicate the angular position of the wheel and thus the kind of leather to be used.

11. A device for measuring the area of shoe parts and calculating the amount of material required for cutting, a tracing arm provided with a tracing point, a radius arm pivoted to the tracing arm, a wheel mounted on the tracing arm to rotate about an axis in the vertical plane of the axis of said arm and having its axis of rotation adjustable angularly with respect to said plane, angular graduations on the tracing arm, the natural cosines of which correspond to the ratios existing between the superficial area of different kinds of leather required to cut the same given shoe parts.

12. A measuring instrument comprising a polar planimeter including a tracing arm and a wheel associated therewith, the wheel having an axis which is arranged for angular adjustment with relation to the tracing arm.

13. A measuring instrument comprising a polar planimeter including a tracing arm and a wheel, the tracing arm carrying an angularly adjustable member in which the wheel is journaled.

In testimony whereof, I have signed my name to this specification, in the presence of two subscribing witnesses.
